UNITED STATES PATENT OFFICE.

ROBERT L. COONEY, OF ATLANTA, GEORGIA.

STATIONARY FIRE-EXTINGUISHER SYSTEM.

1,075,018

Specification of Letters Patent.

Patented Oct. 7, 1913.

Application filed November 29, 1909. Serial No. 530,469.

To all whom it may concern:

Be it known that I, ROBERT L. COONEY, a citizen of the United States, residing at Atlanta, in the county of Fulton and State 5 of Georgia, have invented new and useful Improvements in Stationary Fire-Extinguisher Systems, of which the following is a specification.

This invention relates to new and useful 10 improvements in stationary fire extinguisher systems of the chemical mixing type.

The primary object of the invention is a 15 novel arrangement in which the developed high pressure incident to the chemical mixing action is utilized to operate secondary fire extinguisher agent supply means in a certain, quick and reliable manner and with but slight expenditure of pressure energy.

An embodiment of the invention is shown 20 by way of example in the accompanying drawing, in which the figure is a longitudinal sectional view of an apparatus in accordance with the present invention.

Similar characters of reference refer to 25 corresponding parts.

The character of the chemical mixing apparatus is not essential. The apparatus shown as an example and which forms the basis of my application Serial No. 540,551 30 generally comprehends a tank, as 1, and a distributing pipe, as 2, from which branches lead to the different parts of the building which it is desired to protect. The tank 1 is connected to the pipe 2 by a secondary, (i.e., 35 elastic fluid containing), shell, as 3, to which a barrel 4 is connected. The barrel 4 projects into the tank 1 and therein is provided with a depending pipe, as 5, through which the fire extinguishing agent flows to the 40 distributing system. Within the barrel 4 is a rod 6 which projects inwardly into the tank through an enlarged opening, as 7. The rod 6 is provided with a head 8 which works in the shell 3 and normally closes the end of 45 the barrel 4, and also with a head 9, within the tank 1, and which, when the system is working, closes the opening 7. The acid bottle, as 10, is pivoted off center on a supporting standard, as 11, and to the upper end 50 of the acid bottle a chain, as 12, is connected, the said chain being in turn connected to the inner end of the rod 6. The bottle 10 has a removable closure 10^a.

In the foregoing apparatus, when the 55 dominant pressure in the pipe 2 is reduced as by the opening of a sprinkler head, the

servient pressure in the tank 1 operates positively, i.e., by expansion or projection, to cause an operative movement of the piston 8. This movement produces the overturning of 60 the bottle 10 and the resultant chemical mixing action, it being understood that the tank 1 contains an alkaline solution. Any desired means for equalizing the pressure in the tank and in the distributing pipes and thereby 65 compensating for leakages may be employed. For convenience, a pipe 13, containing a pressure indicator 14, may lead from the pipe 2 and be connected to the tank 1 by a pipe 15 containing an aperture diaphragm 70 or web 16.

The developed pressure, incident to the generation set up in the tank 1, is employed to operate a secondary fire extinguisher agent supply means in a novel manner. The 75 secondary supply means shown herein by way of example involves a service pipe 17 which projects into the tank 1, and a valve 18 for normally closing the end of the service pipe. An efficient valve construction includes an arm 19, carrying the valve 18, and pivoted at its lower end to a bracket 19^a. The force with which the valve 18 bears against the end of the service pipe may be regulated by an adjusting stem 20 which is 80 threaded through the arm 19 and to the inner end of which the valve 18 is secured. By virtue of this arrangement, leakage from the service pipe into the tank may be rendered impossible. The valve 18 is held normally closing the pipe 17, preferably by a pivoted latch lever 21, which has a nose or projection 21^a to engage the free end of the arm 19.

The means for operating the secondary 95 supply means consists essentially of a cylinder 22 which is in open communication with the tank and a piston which moves axially of the cylinder and has but a single operative stroke. This piston, designated by the numeral 22^a, is in the embodiment shown, fitted in the cylinder and is provided with a stem, as 23, which depends into the tank. This stem, at its lower end, is provided with a slot, as 24, through which the free end portion of the latch 21 projects. The piston 22^a normally rests by gravity at the lower 100 end of the cylinder 22. The developed high pressure incident to the chemical mixing action raises the piston 22^a and causes thereby 105 the lifting of the latch lever 21. It follows that the valve 18 is released and when the

pressure in the tank is sufficiently low, assumes its open position so that a secondary extinguishing agent, *i. e.*, in the present instance, water, will flow through the tank and 5 into the distributing system.

I am aware of the construction shown in the U. S. Patent to C. A. Teal, No. 724968, of April 7, 1903, wherein the high pressure incident to the chemical mixing action is utilized to operate a secondary supply pump.

Having fully described my invention, I claim:

1. In a fire extinguisher system, in combination, a distributing pipe, primary fire extinguisher agent supply means consisting of a chemical mixing apparatus, secondary fire extinguisher agent supply means, means for producing a chemical mixing operation and means operable by the developed pressure incident to the mixing operation to provide for an operation of the secondary means, and consisting of a cylinder communicating with the tank, a plunger having a single operative stroke axially of the cylinder and operative connections between the plunger and the secondary supply means.

2. In a fire extinguisher system, in combination, a distributing pipe, a service pipe, a valve controlling the service pipe, chemical mixing apparatus, means for causing a chemical mixing operation, and means normally holding the valve closed and directly operable by the developed pressure incident to the generation set up by the chemical mixing operation to release the service pipe valve and to thereby provide for the opening thereof.

3. In a fire extinguisher system, the combination with chemical mixing means and operating means therefor, of a service pipe, a valve controlling the same, a latch lever normally holding the valve closed, and an element movable by the pressure developed incident to the chemical mixing operation to operate the latch lever to release the valve and to thereby provide for the opening thereof.

4. In a fire extinguisher system, the com-

bination with a fluid driven piston, a service pipe, a valve therefor, a pivoted member carrying the valve, a latch lever normally engaging the pivoted member to hold the valve closed, and operatively connected with the piston, and means for developing an elastic fluid impulse to drive the piston.

5. In a fire extinguisher system, a chemical mixing tank, secondary fire extinguisher agent supply means, a cylinder fitted to the tank in endwise communication therewith, and a plunger movable axially of the cylinder by the developed pressure incident to the chemical mixing action and operative in a single stroke to provide for an operation of the secondary supply means.

6. In a fire extinguisher system, in combination, a distributing pipe, primary fire extinguisher agent supply means consisting of a chemical mixing apparatus, secondary agent supply means comprising a service pipe, a valve controlling the same and a latch lever for the valve, means for producing a chemical mixing operation, and means operable by the developed pressure incident to the chemical mixing action to provide for the operation of the secondary means and consisting of a cylinder communicating with the tank and a plunger having a single operative stroke axially of the cylinder and operatively connected to the latch lever.

7. In a fire extinguisher system, a chemical mixing tank, secondary fire extinguisher agent supply means including a fluid driven controlling element having a single operative stroke and a cylinder in communication with the tank and associated with the element to provide for the direct operation of the latter by the developed pressure incident to the chemical mixing action.

In testimony whereof I have hereunto set my hand in presence of two subscribing witnesses.

ROBERT L. COONEY.
